H. F. LOHMAN & J. HIGHAM.

CAMP STOVE.

APPLICATION FILED APR. 19, 1915. RENEWED AUG. 1, 1916.

1,250,907.

Patented Dec. 18, 1917.

UNITED STATES PATENT OFFICE.

HERMAN F. LOHMAN AND JOHN HIGHAM, OF LOS ANGELES, CALIFORNIA; SAID LOHMAN ASSIGNOR TO SAID HIGHAM.

CAMP-STOVE.

1,250,907.

Specification of Letters Patent. Patented Dec. 18, 1917.

Application filed April 19, 1915, Serial No. 22,279. Renewed August 1, 1916. Serial No. 112,634.

To all whom it may concern:

Be it known that we, HERMAN F. LOHMAN and JOHN HIGHAM, citizens of the United States, residing at Los Angeles, in the county of Los Angeles and State of California, have invented new and useful Improvements in Camp-Stoves, of which the following is a specification.

This invention relates to camp stoves and especially pertains to camp stove structures which may be collapsed and made convenient to transport.

It is the primary object of this invention to provide a stove construction of sheet metal which may be quickly unfolded from its collapsed form, locked in open position and which will be strong and rigid in such opened position.

It is a still further object to provide a stove pipe which is collapsible and when folded can be disposed within the folded stove, thus forming a small package adapted for easy transportation.

The embodiment of our invention disclosed herein comprises a stove which has a body of box-like form with an open front end and an open bottom, the side walls being hinged to the top wall so that they will fold underneath and the back wall being hinged so that it will be folded above. A collapsible stove pipe which is triangular in section is provided, thus forming a structure which may be easily collapsed.

In the accompanying drawing:

Figure 1 is a perspective section of the stove open and ready for use.

Fig. 2 is an enlarged plan view.

Fig. 3 is a vertical section through the stove.

Fig. 4 is a fragmentary section taken on the line 4—4 of Fig. 3.

Fig. 5 is a fragmentary section taken on the line 5—5 of Fig. 4.

Fig. 6 is an enlarged horizontal section taken on the line 6—6 of Fig. 1.

Fig. 7 is a plan view of the stove pipe.

Fig. 8 is a view of the stove pipe collapsed.

More specifically, 9 indicates the top wall of the stove and is preferably of sheet iron, rectangular in form, and having end portions 10, 11 and 12 bent downwardly at right angles to form flanges, whereby a tight joint is provided, thereby preventing smoke from passing outward except by the stove pipe, or

air entering the combustion chamber except at the front opening. Side walls 13 and 14 of rectangular form and preferably of sheet iron, are pivotally secured adjacent the side edges of top wall 9 by means of hinges.

The side walls 13 and 14 have their upper edge portions bent over to form a closed channel within which hinge pin 17 is disposed. The walls have portions cut out to accommodate the leaves 16.

The lower edge of each of the end walls is bent inward to form flanges 20 and 21 which serve as supporting feet when the stove is placed upon the ground. Side walls 13 and 14 are preferably provided with slots 22 and 23 disposed at the rear portion of the wall and with their longest dimension vertical.

Pivots secured to the rear edge of top wall 9 is end wall 24, preferably of sheet iron, and pivoted to the top wall by means of hinge leaves 25 and 26. The side edges of end wall 24 are provided with tongues 27 and 28 adapted to be passed through the slots 22 and 23. Pivots secured to end walls 13 and 14 adjacent slots 22 and 23 are latch hooks 29 and 30 adapted to engage the tongues 27 and 28.

A triangular aperture 31 is formed in the upper wall 9 and is adapted to receive the stove pipe 32 which is in the form of a triangular prism having one wall 33 formed with end flanges 34 and 35 which are turned inward at angles of approximately 60 degrees. Hinge leaves 36 are secured preferably by rivets to wall 33 and are adapted to receive pins 37, which also pass through channels formed by bending wall 38. Wall 38 has one edge bent inward to form a channel for the reception of the hinge pin 37 and slots cut in its edges to accommodate hinge leaves 36. The free end of wall 38 is bent inward at an angle of approximately 60 degrees to form a flange 39. Wall 40 is pivoted to wall 33 by hinge leaves 36, a hinge pin 37, and bent portions which form channels.

In its open form walls 13 and 14 are bent outward until they are stopped by abutting flanges 10 and 12 of top wall 9. End wall 24 is swung downward at right angles to top wall 9, the walls 13 and 14 are sprung outward so that tongues 27 and 28 may be passed through slots 22 and 23. Latch hooks 29 and 30 are then disposed to engage the tongues 22 and 23 and thus securely hold

them in position, the ends 41 of the latch hooks passing through apertures in the tongues. The stove pipe is arranged in open form by swinging walls 38 and 40 outward, 5 the end of wall 40 engaging the inner side of flange 39; the stove pipe 32 is then placed in the aperture in top wall 9.

To collapse the stove, the stove pipe 32 is removed from the aperture in the top wall 9, 10 wall 40 is pushed inward to position indicated in dotted lines in Fig. 7, wall 38 is then swung inward and the collapsed pipe takes the form shown in Fig. 8. Latch hooks 29 and 30 are released from tongues 27 and 15 28. The side walls 13 and 14 are bent outward to disengage the tongues from the slots 22 and 23 and wall 24 is swung upward against the top of the stove. Walls 13 and 14 are then folded inward to positions 20 shown in dotted lines in Fig. 3. The stove and pipe are now in condition to be packed away in a very small space.

Special attention is called to the down-turned flanges at the sides of the top wall, 25 the side walls hinged to the top wall so as to swing outwardly against the flanges, and the end wall hinged to the top wall so as to swing between the ends of the side walls and brace the side walls. This construction produces a very substantial stove when set-up, is 30 easily collapsed, and folds into a very small package.

What we claim is:

1. A collapsible stove, comprising a top 35 wall provided with a stove pipe hole and uninterrupted flanges at its side edges, hinges secured to said top wall adjacent said flanges, side walls secured to said hinges and so disposed that when said stove is open said 40 side walls are in contact with said flanges, an end wall pivoted to said top wall with its edges arranged to be disposed between and in contact with said side walls when the stove is open, said end wall provided with 45 tongues arranged to extend through openings in said side walls when the stove is

open, and catches for engaging said tongues and locking the stove in open form.

2. A collapsible stove, comprising a top wall provided with a triangular stove pipe 50 hole and uninterrupted flanges at its side edges, hinges secured to said top wall adjacent said flanges, side walls secured to said hinges and so disposed that when said stove is open said side walls are in contact with 55 said flanges, an end wall pivoted to said top wall with its edges arranged to be disposed between and in contact with said side walls when the stove is open, said end wall provided with tongues arranged to extend 60 through openings in said side walls when the stove is open, catches for engaging said tongues and locking the stove in open form, a collapsible stove pipe adapted to be disposed in said stove hole comprising a wall 65 having flanges at its sides, hinges adjacent said flanges and two walls secured to said hinges so that when open the last mentioned walls are in contact with said flanges, one of said last mentioned walls having a flange 70 at its free edge arranged to over-lap the other of said last mentioned walls when in open form.

3. A collapsible stove comprising a top wall provided with down-turned flanges at 75 its side edges, side walls hinged to the top wall so as to swing downwardly to vertical positions and engage the flanges, an end wall hinged to the top wall so as to swing between the ends of the side walls and hold the 80 side walls expanded against the flanges, there being slots in the ends of the side walls and tongues extending from the ends of the end wall to snap through said slots, and hooks connected to the outer faces of the side 85 walls to engage said tongues.

In witness that we claim the foregoing we have hereunto subscribed our names this 31st day of March, 1915.

HERMAN F. LOHMAN.
JOHN HIGHAM.
